COMBINED CONTAINER AND CLOSURE THEREFOR

William H. Robinson, Miamisburg, Ohio

Application July 22, 1957, Serial No. 47,038

Term of patent 14 years

(Cl. D58—12.6)

I claim:

The ornamental design for a combined container and closure therefor, as shown.
